N° 22,042.

Patented Nov 9, 1858.

UNITED STATES PATENT OFFICE.

SAMUEL WALKER, OF ROXBURY, MASSACHUSETTS.

FRINGE-LOOM.

Specification of Letters Patent No. 22,042, dated November 9, 1858.

To all whom it may concern:

Be it known that I, SAMUEL WALKER, of Roxbury, in the county of Norfolk and State of Massachusetts, have invented certain Improvements in Fringe-Looms, of which the following is a full, clear, and exact description, reference being had to the accompanying drawings, making part of this specification, in which—

10 Figure 1 is a perspective view of a fringe loom with my improvements attached. Figs. 2, 3, 4, 5, 6, 7, 8, 9 and 10 details to be referred to hereafter.

15 I will first refer briefly to the ordinary and well known parts of the loom and then describe more particularly those features which form the subject of my present invention.

In the said drawings A is the frame work 20 of the loom; B the driving shaft to which motion is communicated in any suitable and customary manner. The warp threads D are carried by a spool or warp beam E and are threaded through a two leaf harness F, 25 actuated in the ordinary manner by treadles and tappets not shown in the drawings.

The reed G is carried by the lathe H which is pivoted at I to the frame work, and is vibrated by direct communications with the 30 driving shaft one of which is seen at K Fig. 1. The weft or fringe thread f is carried by a spool L Figs. 1 and 10 from which it passes through the guide g, thence through the loop h which is of a sufficient weight to 35 keep the requisite tension upon it, and from this loop to the eye in the end of the carrier or finger M. The too free rendering of the thread from the spool L is prevented by the spring k. After the shed has been opened 40 the carrier passes into and through it, and before it returns the knife N rises up into its loop (as seen in Fig. 1) and holds it distended, the knife being set sufficiently far from the warp to make a loop of the required length from the fringe thread. The 45 carrier now returns from out the shed leaving its thread around the knife, and the harness is shifted to change the shed; the knife now descends out of the loop by which the latter is cut. A binding thread m from a 50 spool C (Fig. 9) is interlaced with the two

outside threads of the warp to prevent them from being unraveled; the shifting of this thread is effected in the ordinary manner by the alternate rising and falling of the cords a and b which is effected by the vibration of the drum c, but as this forms no part of my invention it will not be further described. The finished fringe O is wound upon the beam P by a take up motion Q operated by a cord R attached to the lathe H.

The method of operating the carrier M which forms the first part of my invention will now be described. A frame or beam S seen in plan in Fig. 3 is connected by rods n with the lathe H (Figs. 1 and 3) and slides back and forth with it, being guided upon the frame of the loom by rollers p, p. In this frame vibrates the spindle T of the carrier, the hub r of which is furnished with teeth as seen in Fig. 3. With these teeth engage the teeth of a rack-bar V (Figs. 1 and 3) which is vibrated back and forth within the frame or beam S as follows: A face cam V (Fig. 7) upon the main shaft gives 70 through the cords or chains W an alternately up and down motion to the levers X Fig. 1. The forward ends of these levers are connected by means of chains Z with the rack bar U, the chains being so guided by 75 the pulleys t that as the levers X vibrates the bar U shall be reciprocated back and forth a sufficient distance to give the carrier hub r a portion of a revolution, and thus impart to the carrier the required motion in 80 and out of the shed.

The arrangement of the knife and knife holder with the operation of the parts immediately connected therewith will now be described. The knife N is carried by a holder A² secured to the knife lever B², the rear end of which is pivoted to a small standard rising from one of the back beams of the frame work, its forward end entering a hole in the horizontal bar C² which is held 90 up in the position seen in Fig. 1 by springs D² attached to the vertical sliding bars E². When the parts are in this position the knife is elevated to form the loop, as in Fig. 1, and it is depressed to cut the same as follows: To the lower ends of the bars E² are 95 attached the chains F² which after passing

around guide pulleys a' upon the cross timber G^2 are attached to a lever H^2 which is pivoted to the frame work as seen dotted at b' Fig. 1; this lever is also connected by a chain I^2 to a lever K^2 which is also pivoted to the frame and is vibrated each time the driving shaft B revolves by a cam L^2 upon this shaft. The knife bar B^2 and knife N are thus depressed, and the latter is drawn 10 through the loop which is thereby cut. To facilitate this part of the operation, the loop is supported by the stationary bar M^2 the rear end of which is pivoted to the frame work, the forward end resting upon a plate 15 N^2 , while its position horizontally is determined by the pin c' which passes through it and into the bar C^2 . As the bar C^2 rises and descends the pin plays up and down through the support M^2 . To accommodate 20 the loom to the manufacture of different lengths of fringe, the knife is set more or less distant from the warp threads by adjusting its lever B^2 in one or other of the holes d' , the fringe supporter M^2 being 25 brought up immediately behind the knife by changing the position of the pin c' in the bar C^2 ; and in order that the fringe may be held steadily and be prevented from yielding while the loop is being cut, it is 30 passed around pins x upon a bar Y secured to the frame, and seen detached in Fig. 6, but partly covered by the fringe in Fig. 1. That the fringe may be evenly and perfectly formed it is necessary that the loop 35 should not be cut until after the fringe or weft thread be again made fast by the changing of the shed; to insure this end a portion of the lower end of the knife is protected by guard plates i which cover up 40 about one third of the edge, and protect the thread from being cut until the knife has commenced to descend. The back of the knife should be made round and smooth, as when looped or twisted fringe is made the 45 knife is turn half around, that the loops may not be cut. When the loops of fringe are to be twisted in lieu of being cut the fringe thread receives a tight twist at the moment before the loop is formed, this causes the 50 loop so soon as it is free from the knife (which has been turned half around as before stated) to twist up. This is effected as follows: The fringe thread is carried by a bobbin or spool O^2 (Fig. 8) which runs in a head or carriage P^2 to which is attached a pulley f' that is set in motion by a band Q^2 from a pulley R^2 upon a revolving shaft S^2 . This shaft receives its motion from a band 55 T^2 driven by a pulley U^2 upon the shaft B . A sufficiently hard twist is thus put into the fringe thread to cause the loops to twist up in the contrary direction the moment they are freed by the descending knife.

In order that the loops, particularly in 60 making twisted fringe may be held out of

the way while the succeeding loop is being formed, that they may not become twisted up, one within the other, the following device is employed to press each loop down before another is formed: e' is a small 70 toothed wheel having four light fingers i' attached to it. A second wheel g' engages with the wheel f' and is rotated a sufficient distance each beat of the lathe to give the wheel e' a quarter turn as follows: The 75 wheels e' and g' are pivoted to the bar M^2 and upon the pivot of the latter hangs a plate h' (Figs. 1 and 5) which is connected by the cord k' with the beam S and also with a spring X^2 upon the cross bar G^2 in 80 such a manner that as the lathe recedes the plate h' is drawn in the direction of its arrow, and its spring catch l' engages with one of the teeth or pins n' of the wheel g' and revolves this wheel a sufficient distance 85 to carry the fingers i' one quarter around, and as the path of these fingers lies directly over the point where the fringe is formed, the loop last formed is thus carried down beneath the bar M^2 as required; the pins n' are inclined upon one side so that as the lathe again advances and the plate h' is drawn in the direction contrary to its arrow by the spring X^2 , the spring catch l' slips 90 over the pins and takes a new hold ready again to revolve the fingers when the lathe returns.

In order that the fingers i' may always be left in a position ready to depress the loops 95 when they begin to revolve, the wheel e' 100 carries upon one face a square nut or projection m' (Fig. 4) against which rests the spring R' (Fig. 1) attached to the bar M^2 by which the wheel e' is always arrested in 105 a certain determined position. The heddles F are alternately raised and depressed by the rocking of the shaft V^2 produced by cords W^2 attached to treadles in the ordinary way. The drum c which alternately raises and lowers the cords a and b is secured to the shaft V^2 and vibrates with it. 110

Thus far but a single thread carrier and a single set of warps and harnesses has been described; it is contemplated however to multiply the capacity of the loom by the employment of a number of thread carriers, all pivoted to the frame S and actuated by the sliding rack bar U , in conjunction with a corresponding number of heddles suspended from the rocking shaft V^2 by which 115 a number of pieces of fringe may be simultaneously woven.

What I claim as my invention and desire to secure by Letters Patent is—

1. Pivoting the thread carriers to a reciprocating frame S moving with the lathe as set forth for the purpose specified.
2. I claim the guard plates i attached to the knife and operating in the manner substantially as set forth.

3. I claim depressing each loop of fringe as it is formed, by means of the fingers i' or their substantial equivalents, for the purpose of preventing them from being entangled and twisted up with the succeeding loops as set forth.

4. I also claim twisting the weft thread

immediately before the loops of fringe are formed, by pivoting its spool upon a revolving carriage P^2 as set forth.

SAMUEL WALKER.
